UNITED STATES PATENT OFFICE

FRANK O. KUHN, OF SOUTH BEND, INDIANA

ELECTRIC SWITCH

Application filed March 25, 1929. Serial No. 349,761.

My invention relates to switches for lighting circuits and other uses for which the same may be adapted, and has for its object to provide a switch, preferably of the well known 5 toggle type, associated with means whereby the circuit may be closed in the usual manner, but which, upon switching of the button to off position for interrupting the circuit, will not immediately open the circuit, 10 but will set in motion means having a moving force established by a shifting of the switch button whereby to open the circuit and extinguish the lights at a more or less delayed period following the shifting of the switch 15 button to off position, whereby time is provided for the person throwing off the switch to reach a more or less remote point before the switch acts to extinguish the lights.

With the above and other objects in view, 20 the invention resides in the combination and arrangement of parts as hereinafter set forth, shown in the drawing, described and claimed, it being understood that changes in the precise embodiment of the invention may be 25 made within the scope of what is claimed without departing from the spirit of the invention.

In the drawing:

Figure 1 is a side elevation of the switch and 30 controlling mechanism with portions of the frame removed to better show the parts of the device, the full line position being the "on" position, and the dotted line position being the "off" position.

Figure 2 is a top plan view of the device.

Figure 3 is a fragmentary side elevation of 40 the device showing the position of the parts immediately after the switch button has been moved to "off" position.

Figure 4 is a fragmentary longitudinal vertical sectional view of the device taken on line 4—4 of Figure 1, showing parts of the switch in "off" position.

Referring to the drawing, which shows my 45 controlling device used in conjunction with a switch of the well known toggle type, the numeral 10 designates a switch frame, with which are integrally formed the wall plates 11 and the opposite side members 19, between 50 which side members 19 a switch button 12 is

pivotedly secured by means of a pivot pin 13 extending between the opposite sides 19 of the frame 10 and through the plate 14 carried by the switch button at the back side thereof. The plate 14 extends centrally of 55 the switch and projects beyond the ends thereof at 15 and 16, for purposes to be hereinafter set forth, and from the projecting portion 16 extends a rearwardly extending arm 17 having two spaced fingers 18 formed 60 at the end thereof. Each of the sides 19 of the frame extends rearwardly and has integrally formed therewith the spaced diverging arms 20 and 21, and between these diverging arms is disposed one end of a rectangular collar 22, the other end of which collar is disposed in a recess 23 formed in the upper edge of the sides 19, so that the collar member loosely encircles the oppositely disposed arms 20, said recess 23 being located at 70 a point at which the diverging edges of the arms 20 and 21 would meet if projected. Within the collar member 22 and parallel to the sides of the frame is mounted a spring 24, one end of which is seated over an inwardly projecting stud 25 integrally formed with the collar member, and the other end of which is held between the fingers 18 of the arm 17. Mounted on the collar member 22 at one side thereof is an insulated member 80 25a which carries the switch contact members 26 which are adapted to contact with the terminals 27 to close the circuit.

As shown in Figure 2, the side plates 19 of the frame extend rearwardly below and beyond the arms 20 and 21, and carry studs and arbors which support means for controlling the operation of the switch hereinbefore described. Pivotedly mounted on the stud 28 is a tubular member 29, having one end 30 thereof compressed and provided with a slot 31 through which the stud 28 extends, and in which it is free to move. A rod 32, having one end pivotally connected to the projecting portion or end 15 of the plate 14, extends into 90 the tubular member 29, and has a plunger 33, fitting loosely in the tubular member, secured to the inner end thereof. A coil spring 34 is disposed in the tubular member around the rod 32 and has one end thereof bearing 95 100

against the plunger 33 and the other end bearing against the inwardly bent edges 35 of the end of the tubular member, thus resisting movement of the plunger in the tubular member. A pawl 36, pivoted at 37 to the compressed end of the tubular member, is adapted for engagement with the teeth of a gear wheel 38, the movement of which is governed by a spring controlled balance wheel 39 by means of a pallet 40, an escape wheel 41, and a pinion 42, which escapement in structure and function is well known in the horological art. The gear wheel 38 has mounted on one side thereof the studs 43, which are spaced thereon equidistant from each other and from the center of the gear wheel. Pivotally mounted on a stud 44 is a latch member 45 whose lower end is adapted to be engaged by the studs 43 carried by the gear wheel 38 and to be pivoted thereby, and the head 46 of the latch member is adapted to engage the angularly bent end 47 of the rectangular collar 22. A spring 48, secured at one end to one of the side members 19 of the switch frame and at the other end to the latching member above the pivotal point thereof, resists the pivotal movement of the latching member under the influence of the studs 43.

The switch is shown in "on" position in full lines in Figure 1, and in "off" position in Figure 4, and, without the addition of my controlling means, is adapted to operate as follows: Upon upward movement of the switch button 12 to dotted line position in Figure 1, the arm 17 is moved downwardly, carrying one end of the spring 24 with it. The spring is compressed by the downward movement of the arm 17, and when the end of the spring carried thereby has been moved downwardly to a point just below the other end of the spring, or below center, the spring will recoil, forcing upwardly the other end of the spring, and with it the rectangular collar 22 around the stud 25 of which the other end of the spring is seated. When the switch is in "on" position the rectangular collar 22 inclines rearwardly and rests against the upper edges of the arms 21, and when in "off" position rests against the lower edges of the arms 20, the switch contact members 26 being swung away from the switch terminals 27 to the dotted line position shown in Figure 1 upon movement of the collar 22 to "off" position. In turning the switch from "off" position to "on" position, the button is moved downwardly, thus moving one end of the spring 24 upwardly, so that the spring will snap the collar into down position as soon as the end of the spring carried by the arm 17 reaches a point above center, or above the other end of the spring, all as and in the manner of the well known toggle type of switch. With the addition of my controlling means, the operation of the switch is altered as follows: Upon upward movement of the

switch button from "on" to "off" position, the spring 24 is compressed with the end thereof carried by the arm 17 held below center, or lower than the other end thereof, but the collar 22 is prevented from snapping to "off" position by the head 46 of the latching member 45 which engages the end 47 of the collar. The rod 32, carried by the end 15 of the plate 14, is moved to the dotted line position in Figure 1 against the action of the spring 34, and compresses the same, which then pushes against the inwardly bent end of the tubular member 29 to force the tubular member forwardly to a position shown in dotted lines in Figure 1. The speed of the forward movement of the tubular member is governed by the gear wheel 38, against the teeth of which the pawl 36 engages, and the speed of rotation of which is governed by the escapement connected therewith. The rotation of the gear wheel causes one of the studs 43 carried thereby to engage the lower end of the latching member 45 to trip the same after the elapse of a given time as determined by the setting of the escapement, and thus releases the collar 22, which, with the contacts 26 carried thereby, snaps to "off" position under the influence of the compressed spring 24. The tubular member 29, pawl 36, gear wheel 38, studs 43 and latching member 45 are all so arranged with relation to each other that the gear wheel will continue to rotate after the latching member releases the collar 22 until the lower end of the latching member is clear of the stud 43, thus permitting it to assume its normal vertical position under the influence of the spring 48. It will thus be seen that the switch button may be turned to "off" position, but that the circuit will not be interrupted or broken until the elapse of a given length of time thereafter, thus, for instance, permitting a person operating the same to leave the room before the lights controlled thereby are extinguished.

When the switch button is turned from "off" to "on" position, the switch operates to close the circuit immediately and as follows: The button having been moved, the end of the spring 24 carried by the arm 17 is moved upwardly past the center position, causing the collar 26 to be moved downwardly, thus placing the contacts 26 in contact with the terminals 27. The end 47 of the collar 22 strikes the cam shaped upper edge of the head 46 of the latching member, thus causing the same to pivot against the action of the spring 48, which spring causes the latching member to resume its normal vertical position when the collar has reached "on" position. The upward and rearward movement of the end 15 of the plate 14 moves the tubular member 29 to the full line position shown in Figure 1 by means of the rod 32, the pawl 36 being drawn rearwardly over the teeth of the wheel 38 without moving the same, and

the device is then in a position permitting delayed action of the switch upon movement of the switch button to "off" position.

The invention having been set forth, what is claimed as new and useful is:

5. 1. The combination with an electric switch having a shift button, of means controlling said switch to provide a delayed action thereof upon movement of the switch button in one direction, said means comprising a member latching said switch, a power element energized by actuation of the switch button, and an escapement governed means actuated by said power element and adapted to shift said latching member to switch releasing position, said latching member being adapted to relatch said switch upon movement of the switch button in the other direction.
2. The combination with an electric switch having a shift button, of means controlling said switch to provide a delayed action thereof upon movement of the shift button in one direction, said means comprising a member latching said switch, a coil spring having a connection with said shift button whereby said spring will be stressed upon movement of the button in one direction, a longitudinally shiftable member carrying said spring and adapted to be shifted thereby, a pawl carried by said shiftable member, and an escapement governed gear wheel actuated by said pawl and adapted upon a predetermined rotation thereof to trip said latching member, said latching member being adapted to relatch said switch upon movement of the shift button in the other direction.
3. An electric switch comprising a shift button, a circuit controller actuatable by and having a yielding connection with said button, a latch member for holding the controller against movement upon shifting of the button in one direction, means for tripping the latch member, and means for driving said tripping means having a moving force established by the shifting of the shift button, said shift button directly actuating the circuit controller upon movement thereof in the opposite direction.
4. An electric switch comprising a shift button, a circuit interrupter actuatable by and having a yielding connection with said button, a latch member for holding the interrupter against movement, a gear wheel having trip pins for tripping said latch member, a shiftable member carrying a pawl engaging the teeth of the gear wheel, a spring normally unstressed engaging the shiftable member, and a connection between said spring and the shift button whereby the same will be stressed upon movement of the shift button to off position.

5. An electric switch comprising a shift button, a circuit interrupter actuatable by and having a yielding connection with said button, a latch member for holding the inter-

rupter against movement, a gear wheel having trip pins for tripping said latch member, an endwise shiftable member carrying a pawl engaging the teeth of the gear wheel, a coil spring normally unstressed carried by the shiftable member, a connection between said spring and the shift button whereby the same will be stressed by a movement of the shift button to off position, and means for governing the speed of rotation of the gear wheel.

6. An electric switch comprising a shift button, a circuit controller actuatable by and having a yielding connection with said button, a latch member holding the controller against movement upon shifting of the button in one direction, a trip member adapted to trip said latch member, means actuated by said movement of the shift button to operate the trip member, and means controlling the operation of said last named means under a delayed action, said shift button directly actuating the circuit controller upon movement thereof in the opposite direction.

7. An electric switch comprising a shift button, a circuit controller actuatable by and having a yielding connection with said button, a latch member holding the controller against movement upon shifting of the button in one direction, a trip member adapted to trip said latch member, and a spring actuated by said movement of the shift button for operating the trip member under a delayed action to release said latch member, said shift button directly actuating the circuit controller upon movement thereof in the opposite direction.

8. An electric switch comprising a shift button, a circuit controller actuatable by and having a yielding connection with said button, a latch member holding the controller against movement upon shifting of the button in one direction, and means actuated by said movement of the shift button to release the latch member in predetermined timed relation to said movement of the shift button, said shift button directly actuating the controller upon movement thereof in the opposite direction.

9. An electric switch comprising a shift button, a circuit controller actuatable by and having a yielding connection with said button, a latch member holding the controller against movement upon shifting of the button in one direction, means actuated by said movement of the shift button to release the latch member, and means controlling the operation of said last named means under a delayed action, said shift button directly actuating the controller upon movement thereof in the opposite direction.

10. An electric switch having a shift button, a circuit controller actuatable by and having a yielding connection with said button, a latch member holding the controller

against movement upon shifting of the button in one direction, a spring, a member shifted by movement of said button to energize said spring and adapted to release said latch member under the action of said spring, and 5 means governing the action of said spring in timed relation to the shifting of the shift member, said switch button directly actuating said circuit controller upon movement thereof in the opposite direction.

10 11. An electric switch having a shift button, a circuit controller actuatable by and having a yielding connection with said button, a latch member holding said controller against 15 movement upon shifting of the button in one direction, a shiftable member having connection with said shift button, and means energized by shifting of the shiftable member to release said latch member under a delayed action, 20 said switch button directly actuating said circuit controller upon movement thereof in the opposite direction.

12. An electric switch having a shift button, a circuit controller actuatable by and having a yielding connection with said button, a latch member holding said controller against movement upon shifting of the button in one direction, a spring, a member shifted by movement of the button to energize said 25 spring, means driven by said spring to release said latching means, and means retarding the releasing means under a delayed action, said switch button directly actuating said circuit controller upon movement thereof in the opposite direction.

30 35 In testimony whereof I affix my signature.
